UNITED STATES PATENT OFFICE.

GEORGE HENRY WHEARY, OF RACINE, WISCONSIN.

TRUNK SHOE-BOX.

1,171,394.

Specification of Letters Patent. Patented Feb. 8, 1916.

Application filed October 5, 1914. Serial No. 864,976.

To all whom it may concern:

Be it known that I, GEORGE HENRY WHEARY, a citizen of the United States, and resident of Racine, in the county of Racine 5 and State of Wisconsin, have invented new and useful Improvements in Trunk Shoe-Boxes, of which the following is a description, reference being had to the accompanying drawings, which are a part of this specification.

This invention relates to improvements in trunk shoe box more particularly adapted for use in connection with wardrobe trunks.

It is desirable in wardrobe and other like trunks to provide shoe containers which are usually in the form of boxes generally positioned within the lower portion of the wardrobe section of the trunk. The boxes usually rest upon the lower end portions of the said 20 sections and are detachably connected to the side walls thereof and it is necessary to remove the boxes from the section in order to open the cover to gain access to the box, as the covers are usually formed on the inner 25 sides of the boxes. As thus positioned and arranged comparatively considerable time is required to remove or place shoes within the box, and furthermore the boxes as thus mounted within the section are often broken, 30 due to the lower end of the wardrobe section being forced inwardly in dropping the trunk on its end.

It is one of the objects of the present invention to overcome the before mentioned 35 and other objectionable features and provide a trunk shoe box which is so constructed and mounted within the trunk section that it may be easily swung to a position of convenient accessibility without detaching the 40 box from the trunk section.

A further object of the invention is to provide a trunk shoe box which is so positioned and mounted within the trunk section that it cannot be injured by any normal 45 shocks which trunks are usually subject to.

A further object of the invention is to provide a trunk shoe box possessing the features before mentioned and which may be easily removed from the trunk section when 50 desired.

A further object of the invention is to provide a trunk shoe box which is simple in construction, is inexpensive to manufacture, is strong and durable and is well adapted 55 for the purpose described.

With the above and other objects in view the invention consists of the improved trunk shoe box and its parts and combinations as set forth in the claims and all equivalents thereof.

In the accompanying drawing in which the same reference characters indicate the same parts in all of the views: Figure 1 is a front view of a wardrobe trunk section provided with the improved shoe box; Fig. 2 is a transverse sectional view thereof taken on line 2-2 of Fig. 1; Fig. 3 is a sectional view of the lower portion of the trunk taken on line 3-3 of Fig. 2; Fig. 4 is a sectional detail view of one of the shoe box latches and 70 connected parts; Fig. 5 is a fragmentary front view of a modified form of shoe box attaching means; Fig. 6 is a sectional view thereof taken on line 6-6 of Fig. 5; and Fig. 7 is a fragmentary detail view of one 75 of the locking plates.

Referring to the drawing the numeral 10 indicates a wardrobe trunk, 11 the drawer section and 12 the wardrobe section which is provided with the improved shoe box 13. 80

The shoe box 13 is of rectangular form and is provided with a cover 14 on its inner side which is hinged to the bottom edge portion of the box and has a strap and snap connection 15 at its upper edge portion so that when the box is swung outwardly from said section the box opening and cover will be on top. The interior portion of the box may be divided into as many compartments as desired. Trunnion plates 16 mounted on the opposite side edge portions of the box near the lower portions thereof are provided with headed trunnions 17 which engage locking plates 18 mounted within and on the opposite side walls of the wardrobe section of the trunk. The locking plates are provided with elongated slots 19 adapted to receive the headed trunnions of the box plates. The entrance portions 20 of the slots 19 extend rearwardly a short distance and the slots are then curved downwardly and forwardly to form locking shoulders 21, and are then extended downwardly a short distance as indicated by the numeral 19' to permit vertical play of the trunnions 17. The trunnions form a removable and a pivotal connection with the plates so that the shoe box may be swung out of the wardrobe section to a position of convenient accessibility and as indicated in Fig. 110

6. Medial portions 22 of the locking plates are offset from the side walls to provide space therebetween to accommodate the heads 17' of the trunnions. As the stem portions of the trunnions enter the slots of the locking plates the trunnion heads serve to reinforce the side walls against bulging outwardly and the box serves to reinforce the said walls against outer strains.
- 10 Spring actuated bolts 23 mounted on the upper corner edge portion of the box are adapted to snap into locking engagement with the locking plates 24 mounted within the wardrobe section and on opposite side walls thereof. The inclosing casings of the bolts 23 are provided with hook portions 25 which hook over the edge portions of the plates 24 to reinforce the side walls of the wardrobe section in the same manner described with reference to the trunnions 17.

In using the shoe box described it is only necessary to release the bolts and swing the box outward and the box cover may then be swung upwardly to gain access to the interior thereof, and in swinging the box upwardly to closed position the bolts will automatically snap into locking engagement with the plates.

- 30 In the modified form shown in Figs. 5, 6 and 7 the manner of securing the box to the trunk is slightly different from the first form described. In this form the trunnion plates 16' are provided with upper and lower headed trunnions 26 and 27 and the locking plates 28 are provided with upper and lower elongated slots 29 and 30 (only one of each being shown) to receive the upper and lower trunnions respectively.
- 40 The entrance openings 30' of the lower slots extend rearwardly a short distance and the slots are then curved downwardly and forwardly to form the locking shoulders 31 and are then extended downwardly a short distance as indicated by the numeral 32 to permit vertical play of the lower trunnions 27. These lower trunnions are connected to the plates in substantially the same manner before described and operate in the same manner.

The upper trunnions 26 are of the same shape as the lower trunnions and are adapted to have a locking engagement with plates 28 by means of the upper slots 29. These slots have their entrance openings 29' extending rearwardly for a short distance and the slots are then curved downwardly and forwardly to form locking shoulders 33 and flat springs 34 mounted on the locking plates 28 yieldingly hold the trunnions in locked position beneath the said locking shoulders 33. The slots 29 and 30 are so spaced with reference to the distance apart of the trunnions 26 and 27 that when the trunnions 27 are pulled upwardly into the vertical por-

tions 32 of the slots 30, the upper trunnions 26 may be swung into the entrance openings of the slots 29 and the box may then be pushed downwardly to locked position. When in locked position and it is desired to swing the box to an accessible position it is only necessary to pull upwardly and rearwardly on the box and then forwardly on the upper end thereof to unlock said upper end and the holder may then be swung out of the wardrobe section. If it is now desired to detach the box from said section the lower end of the box is raised and then moved upwardly, rearwardly and forwardly to pass over the locking shoulders of the lower slots to disengage the locking plates. Medial portions of the locking plates 28 are offset from the side walls of the trunk section to provide space therebetween to accommodate the heads of the trunnions.

The numeral 35 indicates one of the garment hangers which is slidably mounted on tracks 36 secured to the side walls of the trunk section and is adapted to have garments suspended thereon.

From the foregoing description it will be seen that the shoe box is well adapted for the purpose described.

What I claim as my invention is:

1. The combination with a trunk provided with a removable box having an inner open side and a hinged cover, of a means for securing the box to the trunk, comprising trunnions and slotted plates interposed between the opposite side portions of the box and the side walls of the trunk, said trunnions and plates forming a detachable and a pivotal connection between said trunk walls and the box, and means releasably locking the upper portion of the box to the trunk.

2. The combination with a trunk, of a box therefor, comprising a box-like member having an open side and a hinged cover, said box being positioned in the lower portion of the trunk with its lower part spaced a distance above the lower part of the trunk to permit inward movement of said trunk part without injury to the box, trunnions and slotted plates interposed between the opposite side portions of the box and the side walls of the trunk, said trunnions and plates forming a detachable and a pivotal connection between the said trunk walls and the box, and means releasably locking the upper portion of the box to the trunk walls.

3. The combination with the wardrobe section of a trunk, a box positioned in the lower portion of said section and having its lower edge portion spaced above the lower wall of said section, said box having an inner open side and a hinged cover therefor, means pivotally connecting the lower portion of said box to the trunk section to permit the upper portion of said box to be

swung outwardly from said section, and means locking the upper portion of said box against outward movement.

4. The combination with the wardrobe section of a trunk, a box positioned in the lower portion of said section and having its lower edge portion spaced above the lower wall of said section, said box having an inner open side and a hinged cover therefor, the lower edge portion of said cover being hinged to the lower portion of the box, means detachably and pivotally connecting the lower portion of said box to the trunk section to permit the upper portion of the box to be swung outward from said section, said means com-

prising trunnions and slotted plates, and means locking the upper portion of said box against outward movement, means pivotally connecting the lower portion of said box to the trunk section to permit the upper portion of said box to be swung outward from said section, and means locking the upper portion of said box against outward movement. 20

In testimony whereof, I affix my signature, in presence of two witnesses. 25

GEORGE HENRY WHEARY.
